UNITED STATES PATENT OFFICE.

FRANK H. SCHWERIN, OF WEST VIEW, PENNSYLVANIA, ASSIGNOR TO THE DUFF MANUFACTURING COMPANY, OF PITTSBURGH, PENNSYLVANIA, A CORPORATION OF PENNSYLVANIA.

TRIP JACK.

Application filed May 12, 1922. Serial No. 560,351.

To all whom it may concern:

Be it known that I, FRANK H. SCHWERIN, a citizen of the United States, and a resident of the borough of West View, in the county of Allegheny and State of Pennsylvania, have invented a new and useful Trip Jack, of which the following is a specification.

The object of the invention is to provide an economical and efficient trip jack mechanism and particularly to provide novel and advantageous means and organization whereby the jack can be tripped with slight effort and with security against re-engagement.

In the accompanying drawings, forming a part hereof:

Fig. 1 is a side elevation of the jack with the operating lever socket raised, the parts being shown in full lines in engagement with the rack and broken lines being used to show how the lifting pawl may be tilted rearward away from the rack preparatory to tripping;

Fig. 2 is an enlarged fragmentary sectional elevation, the plane of the section being substantially central of the pawl mechanism, which is shown in the tripped condition;

Fig. 3 is a sectional rear elevation of Fig. 2, the section being taken in the vertical axial plane of the main bearing pin, which is seen in elevation;

Fig. 4 is a perspective view of the trip; and

Fig. 5 is a perspective view of the holding pawl.

The jack has a frame 1, with a toothed rack-bar 2 slidable therein and provided at the top with a jacking head 3 and at the bottom with a foot-step 4. Pivoted in the rear upper portion of the frame on a main bearing pin 5 is the rocker socket 6 of an operating lever. As seen more particularly in Fig. 3 the end portions of the pin are received in openings in bosses 7 of the frame, and bushings 8 are interposed between these end portions and the frame, the bushings projecting a short distance into the interior space of the frame. The rocker is supported on the central portion of the pin between the bushings, the inwardly projecting portions of which are encircled by the openings of the limbs 9 of a bifurcated holding pawl 10. Pivoting the holding pawl on the main axis

affords the most advantageous angular relation between the pawl and rack for purpose of tripping, and the coaxial pivot supports have been devised as described in order to distribute the stresses and brace the pin. 55

A lifting pawl 11 is pivoted in a notch in the forward upper portion of the lever rocker, and is adapted to be tilted backward away from the rack through the opening of the holding pawl. This can be done by reaching in with the finger or with a hook, or otherwise. 60

Pivoted on a transverse pin 12 in the frame above the pawls is a trip 13, this trip having a downturned nose 14 adapted to press rearward against the front of the upper portion of the holding pawl, and a depending tail 15 formed with a notched extremity 16 adapted to receive and be acted upon by the tip of the lifting pawl when the latter is tilted back past the vertical. 65

This can be done when the operating lever is in its upward position, shown in Fig. 1. Then, upon swinging the lever down, the lifting pawl is caused to work against the tail, swinging the trip slightly rearward and nosing the holding pawl clear of the rack, which is then free to drop. Because of the shortness of the nose compared with the length of the tail, and the angular relations, the displacement of the holding pawl under load is effected very easily. 75

When the pawls are disengaged from the rack as shown in Fig. 2, the mechanism locks itself by virtue of the engagement of the tip of the lifting pawl with the tail of the trip arm 13 and the rearwardly-bent toggle relation between these parts, which necessitates raising of the operating lever before the pawls, or either of them, can re-engage with the rack. This insures that while the rack is dropping the pawls can not rebound into engagement with the rack teeth, with destructive effect. When the operating lever is raised from the position of Fig. 2, the angular lock between the elements 11 and 13 is broken, these parts are 80

disengaged and the pawls being no longer restrained will return to the rack. 95

The nose 14, it will be observed, is duplex, comprising two laterally spaced, duplicate portions, which straddle the beak 17 of the holding pawl to work upon forwardly fac- 100

ing shoulders 18 on this pawl at opposite sides of the beak. This has the effect of balancing the thrust in the tripping operation. In the lifting operation the holding pawl 5 oscillates between the nose and tail of the trip without interference.

While the preferred embodiment of the invention has been described in detail, it will be understood that various changes may 10 be made without departing from essentials.

What I claim as new is:

1. In a trip jack, a frame, a rack, an operating lever, a lifting pawl operated by the lever, and a holding pawl, in combination 15 with a trip pivoted on the frame above the pawls having a downturned nose adapted to act upon the front of the upper portion of the holding pawl and a depending tail to be engaged by the lifting pawl 20 when the latter is tilted back away from the rack.

2. In a trip jack, the combination of a frame, a rack, an operating lever fulcrumed in the frame, a bifurcated holding pawl pivoted on the fulcrum of the operating lever, a lifting pawl pivoted on the operating lever and tiltable rearward through the opening of the holding pawl, and a trip pivoted on the frame above the pawls 25 and having a downturned nose adapted to act upon the front of the upper portion of the holding pawl and a depending tail to be engaged by the lifting pawl when the latter is tilted back away from the rack.

3. In a trip jack, a frame, a rack, an operating lever, a lifting pawl operated by the lever, and a holding pawl, in combination with a trip pivoted on the frame above the pawls having a downturned nose adapted to 40 act upon the front of the upper portion of the holding pawl and a depending tail having a notched extremity for engagement by the lifting pawl when the latter is tilted back away from the rack.

4. In a trip jack having a frame, a rack, and an operating lever, a lifting pawl operated by the lever, a holding pawl having shoulders at opposite sides of its beak, and a trip pivoted on the frame above the pawls 50 and having a duplex nose adapted to act with balanced thrust upon said shoulders and a depending tail to be engaged by the lifting pawl when the latter is tilted back away from the rack.

5. In a trip jack having a frame and a rack, a main bearing pin supported at its ends in the frame, inwardly projecting bushings interposed between the end portions of the pin and the frame, an operating lever 60 on the central portion of said pin, a bifurcated holding pawl having its limbs on the inner end portions of the bushings, a lifting pawl pivoted on the lever and movable backward through the opening of the holding pawl, and a trip pivoted on the

frame above the pawls having a nose to act upon the holding pawl and a tail to be acted upon by the lifting pawl.

6. In a trip jack having a frame and a rack, the frame having main bearing openings, inwardly projecting bushings in said openings, a main bearing pin supported in said bushings, an operating lever supported on the central portion of said pin between the bushings and carrying a lifting pawl, and a bifurcated holding pawl having its limbs supported on the inner end portions of said bushings. 70

7. In a trip jack, the combination of an operating lever, a lifting pawl, a holding pawl, and a trip pivoted on the jack frame above the pawls and having a nose to act upon the holding pawl and a tail to be acted upon by the lifting pawl. 75

8. In a trip jack, the combination of an operating lever, a lifting pawl, a holding pawl, and a trip pivoted on the jack frame above the pawls, said trip having a tail to be acted upon by the lifting pawl and a nose comprising laterally spaced portions 80 straddling the beak of the holding pawl. 85

9. In a trip jack having a frame and a rack, the combination of an operating lever, a lifting pawl, a holding pawl, and a trip lever on the frame constituting a separate 90 intermediate element adapted to be actuated through the lifting pawl when the latter has been tilted back to throw out the holding pawl. 95

10. In a trip jack, a frame, a bifurcated holding pawl, a main bearing pin, an operating lever fulcrumed on the central portion of said pin and carrying a lifting pawl, and inwardly projecting bushings in opposite sides of the frame together supporting 100 said pin and affording trunnions whereon the holding pawl is supported independently of the pin. 105

11. In a trip jack, having a rack, an operating lever, a lifting pawl pivoted thereon, a holding pawl, and a trip arm depending from the frame above the lever and lifting pawl and adapted to be engaged by the lifting pawl when the same is tilted back and the lever is then depressed, whereby the holding pawl is disengaged from the rack and the parts lock themselves after the manner of a toggle as long as the lever remains down. 110

12. In a trip jack, having a rack, an operating lever, a lifting pawl pivoted thereon, a holding pawl, and a trip arm depending from the frame above the lever and lifting pawl and having a notched end 120 adapted to be engaged by the lifting pawl when the same is tilted back and the lever is then depressed, whereby the holding pawl is disengaged from the rack and the parts lock themselves after the manner of a toggle as long as the lever remains down. 125

130

13. In a trip jack, having a rack, an operating lever, a lifting pawl pivoted thereon, a holding pawl pivoted at its lower end in the frame and normally tilted forward against the rack, and a trip lever separate from the pawls fulcrumed on the frame above the lever and lifting pawl and arranged to act rearwardly upon the hold-
- ing pawl, the trip lever having a depending arm or tail adapted to be engaged when the lifting pawl is tilted back and the lever is then depressed, whereby the holding pawl is disengaged from the rack and the parts lock themselves as long as the lever remains down.

FRANK H. SCHWERIN.
